DESIGN FOR A DABBING BRUSH

Clarence G. Rowland, North Newington, Conn.,
assignor to The Fuller Brush Company, Hartford, Conn., a corporation of Connecticut

Application December 19, 1940, Serial No. 97,466

Term of patent 14 years

To all whom it may concern:

Be it known that I, Clarence G. Rowland, a citizen of the United States and a resident of North Newington, in the county of Hartford and State of Connecticut, have invented a new, original, and ornamental Design for a Dabbing Brush, of which the following is a specification, reference being had to the accompanying drawing, forming part thereof, in which—

Figure 1 is a bottom plan view of a dabbing brush showing my new design.

Figure 2 is an edge elevational view of the same.

Figure 3 is a top perspective view of the same.

I claim:

The ornamental design for a dabbing brush, as shown.

CLARENCE G. ROWLAND.
